SWITCHING APPARATUS

Earl K. Clark, Mansfield, Ohio, assignor to Westinghouse Electric & Manufacturing Company, East Pittsburgh, Pa., a corporation of Pennsylvania

Application December 13, 1940, Serial No. 370,049

14 Claims. (Cl. 200—38)

My invention relates to switching apparatus, more particularly to time-controlled switching apparatus, and has for an object to provide improved apparatus of this kind.

A further object of the invention is to provide a novel double-throw, time-controlled switching apparatus, movable through an open position wherein preliminary sequential operation of the switching members is effected, as the apparatus is moved from one closed position to a second closed position.

A further object of the invention is to provide manually-operated switching apparatus of the kind set forth wherein the apparatus may be actuated manually in one direction from one closed position through an open position to a second closed position and, when actuated manually in a reverse direction, movement of the apparatus to its open position only is effected.

A further object of my invention is to provide a time-controlled, double-throw switching apparatus manually movable from a first closed position to a second closed position and movable from the second to the first closed positions only with the assistance of the timing mechanism.

A still further object of the invention is to prevent short circuits in a double-throw, time-controlled switching mechanism.

It is a still further object of the invention to provide an improved time-controlled switching apparatus having a plurality of switching members operated sequentially as the apparatus is moved from one position to a second position, wherein, manually-operated means is provided for completing the sequential operations of the switching members when the manually-operated means is adjusted in one direction and wherein a portion of the sequential operations of the switching members is effected by the time-controlled means upon adjustment of the manually-operated means in a reverse direction.

These and other objects of this invention will be apparent from the following description and claims taken in connection with the accompanying drawings forming a part of this application, in which:

Fig. 1 is a front view of a preferred embodiment of a time-controlled switch constructed in accordance with this invention;

Fig. 2 is a front view of the switch shown in Fig. 1 with the operating handle and switch casting cover removed;

Fig. 3 is a bottom view of the switch shown in Figs. 1 and 2;

Fig. 4 is a sectional view of the switch shown

in Figs. 1 to 3 taken substantially on the line IV—IV of Fig. 2;

Fig. 5 is a central transverse sectional view of the switch taken substantially along the line V—V of Fig. 2;

Fig. 6 is a rear view of the switch handle structure as viewed from the plane VI—VI in Fig. 5; and,

Figs. 7 to 11, inclusive, are diagrammatic views showing relative positions of various elements of the handle for different operating positions thereof.

This invention is herein disclosed particularly with respect to a switching means comprising a plurality of switches actuated in predetermined relation by a single switch actuating cam member, together with a timing mechanism which is manually adjustable to select any desired time interval during which the switches are adjusted to one position. At the end of the time interval selected, the timing mechanism actuates the switches to another controlling position. The specific switch disclosed herein is particularly adapted for use in controlling heater circuits of the type employed in an electric range or the like. Such circuits are shown, for example, in the copending applications of C. H. Hodgkins, Serial No. 369,819, filed December 12, 1940 and E. K. Clark, Serial No. 368,495, filed December 4, 1940, both of which are assigned to the assignee of the present application.

Although this particular switching means is especially designed for use in the heating circuit disclosed in the above-mentioned copending application, wherein it has certain particular novel features of cooperation therewith, it is at the same time capable of use in other circuits for controlling other types of electrical apparatus. The switch disclosed is not only adapted to have two controlling positions by virtue of the fact that certain of the switches incorporated therein are of the double-throw type, but the switch has the further feature of providing a sequential operation of certain of the switches when the control means is initially moved to select a predetermined time interval for maintaining the switches in one active position, and this sequential operation obviously will also take place at the end of the time interval in a reverse sequence.

The reason for providing sequential operation of certain of the switches preferably, is to obtain a time interval between the operation of the switches. Where the switches may also be manually operated, this purpose may be defeated if the operator quickly moves the switch control

means so that the sequentially-operated switches are actually operated substantially simultaneously. In order to provide against such an occurrence, the switch disclosed is arranged so that sequential operation of the contacts can take place at least upon movement of the switch control in one direction, only under the influence of the timing mechanism, to thereby preserve the time delay between succeeding switch operations.

The switch illustrated is preferably supported in an insulating casing 10 of any desired insulating material, preferably a molded insulating material, with the casing 10 having a bottom wall 11, side walls 12, 13, 14 and 15, and an open front face. Suitably secured on the bottom wall of the casing at one end thereof are terminals 16, 17 and 18. Mounted within casing 10 in adjacent corners thereof, respectively, are switch blade supports 19 and 21, conductively connected to terminals 16 and 18, respectively, for supporting switch blades 22 and 23. These switch blades are preferably of a resilient conducting material so as to be normally biased into engagement with fixed contacts 24 and 25, respectively, mounted on bottom wall 11 in opposite corners of casing 10. Switch blades 22 and 23 may be moved into engagement with fixed contacts 26 and 27, respectively, also mounted on bottom wall 11. Contacts 27, 25, 26 and 24 are mounted on supports extending through the bottom wall 11 of casing 10, to provide terminals 28, 29, 31 and 32, respectively, at the outer side thereof. Contacts 26, 24 and 27, 25 are located in restricted arcing chambers, formed by baffle members 33 in the casing integral with side wall 13 and bottom wall 11, and by an insulating cover plate 34 overlying the baffles and contacts, to form arc chambers of insulating material having an opening merely to accommodate movement of the switch blades 22 and 23. Terminal 17 is conductively associated with a contact 35 shown in Fig. 4 and cooperating with a switch blade 36 mounted in the casing on the bottom wall 11 thereof. Switch blade 36 (Fig. 4) is conductively associated, through bottom wall 11 of casing 10, with a terminal strap 37. It will be noted that the contact 35 is also positioned in a restricted arc chamber formed by a recess 38 in casing 10.

Switch blades 22, 23 and 36 are actuated by a single cam member 39 in the form of a block of insulating material having a substantially central opening therethrough, so as to be rotatably mounted on a shaft 51 secured in the bottom wall of casing 10. Cam member 39 is circular in form, and is provided on its periphery with upper and lower cam surfaces 42, 43 for actuating switch blades 22 and 23, respectively. By reference to Figs. 2 and 5, it will be noted that switch blades 22 and 23 are provided with relatively offset cam rollers 44 and 45, respectively, for cooperation with peripheral cam surfaces 43 and 42, respectively, on cam member 39. Cam member 39 is also provided with a recess 46 in its undersurface for cooperation with a struck-up portion 47 on switch blade 36, to actuate switch blade 36 in a predetermined sequence with respect to switch blades 22 and 23. Cam member 39 is provided in its upper surface with a pair of spaced sockets 48 adapted to receive a correspondingly spaced pair of driving prongs 49 fixed to the shaft 51 of a timing mechanism, generally indicated at 52. The driving prongs 49 project through an opening in insulating plate 34 and are received in sockets 48 in the cam member for driving engagement therewith.

It will be noted that operating cam 39 is provided with opposed substantially identical raised and depressed cam portions connected by intermediate cam portions 53 and 54 (see Fig. 2). It will be obvious that when cam block 39 is rotated in a clockwise direction, as viewed in Fig. 2, the cam rollers 44 and 45 on switch blades 22 and 23, respectively, will engage the intermediate cam portions 53 and 54 to be moved thereby to a position intermediate their associated contacts 26, 24 and 28, 27. It will also be noted that just prior to engagement of cam portions 53 and 54 with the switch blade rollers that the struck-up portion 47 on switch blade 36 will enter slot 46 in the lower face of cam block 39 to thereby permit switch blade 36, which is normally biased upwardly, to separate from its cooperating contact 35. Separation of switch blades 22 and 23 from their contacts 24 and 25, respectively, then occurs, after which the blade rollers 44 and 45 ride onto the outer raised portions of the cam block and move the switch blades into engagement with the outer contacts 26 and 27, respectively. Rotation of cam block 39 in a counterclockwise direction will provide a reverse sequence of operation; that is, switch blades 22 and 23 will first be moved out of engagement with contacts 26 and 27, respectively, to a position intermediate their associated contacts and out of engagement therewith, after which the switch blades are permitted to close to inner contacts 24 and 25, and finally the end of slot 46 in cam block 39 is reached and blade 36 is forced into engagement with contact 35.

The timing mechanism 52 is provided with a coil spring 55, one end of which is connected to drive shaft 51, and the other end of which is connected to the timer frame as at 56. Drive shaft 51 has a gear 57 (Fig. 5) rotatably mounted thereon and frictionally secured for movement with the shaft by a resilient cup-shaped washer 58 keyed to the shaft and frictionally engaging gear 57. Gear 57 meshes with a pinion gear 59, the latter operating an escapement mechanism (not shown) in a well-known manner. The switching structure, including the timing mechanism, described heretofore, is the invention of C. H. Hodgkins and is disclosed and claimed in his copending application Serial No. 369,820, filed December 12, 1940.

The open-ended switch casing 10 is closed by a plate 61 which is secured to the switch casing by screws 62. The shaft 51 extends through a suitable opening formed in the plate 61 and carries a handle mechanism, generally indicated by the numeral 63, at its outer end. The handle mechanism 63 includes a rotatable knob 64, preferably of insulating material and having an insert or collar 65 secured therein. An outwardly-extending arm 66 is secured to the lower end of the collar 65 and moves with the collar 65 at all times. The knob 64 and its insert 65 are loosely carried by the shaft 51 so that angular movement of the knob 64 and insert 65 relative to the shaft 51 is afforded during some periods of operation, as described hereinafter. Axial movement of the knob 64 relative the shaft 51 is prevented by a set screw 67 which extends within an annular slot 68 formed at the end of the shaft 51.

An index carrier 69, having an index 73 (Figs. 1 and 7) formed thereon, frictionally engages, at its inner end, the collar 65 and, when unrestrained, moves angularly with the knob 64 and collar 65. The outer end of the carrier 69 is

disposed between stops 71 and 72 fixed to the cover plate 61, which stops 71 and 72 limit angular movement of the index carrier 69. The index 73 cooperates with graduated indicia 74 formed on the front surface of the knob 64. As shown in Figs. 7 to 11, inclusive, the indicia 74 represents number of minutes.

A driving connection between the handle 64 and the shaft 51 is provided by an arm 75 which is fixed to the shaft 51 and which carries a pin 76 adjacent its outer end. The pin 76 extends within an elongated opening 77 formed in the arm 66. A tension spring 78 provides a bias between the arms 66 and 75 and tends to move the arm 66, handle 64, and index carrier 69 counterclockwise with respect to the arm 75 as viewed in Figs. 7 to 11, inclusive. Counterclockwise movement of the knob 64 beyond the position shown in Fig. 7 is prevented by a projection 79 formed on the undersurface of the knob 64, which projection engages the index carrier 69 in the position of the apparatus shown in Fig. 7.

The switch apparatus described heretofore is adjustable to first and second active or circuit-closing positions between which there is an inactive or "off" position. The apparatus as shown in Figs. 1 to 7, inclusive, is disposed in its first active position wherein the switch blades 22 and 23 engage their respective stationary contacts 24 and 25 and wherein the switch blade 36 engages its contact 35. The positions of the arms 75 and 66 and the handle 64 in this first active position of the apparatus is shown in Fig. 7. In this first active position, a three-wire circuit is established wherein the terminal 16 is electrically connected to the terminal 31, the terminal 18 is electrically connected to the terminal 29, and the terminal 17 is electrically connected to the terminal 37. Adjustment of the switching apparatus through its inactive position to the second active or closed position will now be described.

The period of time that the apparatus is to be retained in its second active position is variable up to thirty minutes in the particular embodiment which I have disclosed, at the end of which time it is first moved to its inactive or "off" position and thence to the first active position as shown in the drawings. Adjustment of the apparatus for fifteen minutes operation in its second active position may be effected by moving the knob 64 angularly, clockwise from the position shown in Fig. 7 to the positions shown in Fig. 9. This angular clockwise movement of the knob or handle 64 effects clockwise movement of the arm 66. As the pin 76 engages the arm 66, clockwise movements of the arm 75 and shaft 51 are also effected. Movement of the shaft 51, of course, winds the spring 55 of the clock mechanism. During the initial clockwise movement of the knob 64, the index carrier 69 moves with the knob because of its frictional engagement therewith until the carrier 69 engages the stationary stop 72 as shown in Fig. 8. In the example illustrated, this movement of the knob 64 (from Fig. 7 to Fig. 8) represents three minutes of reverse rotation of the shaft 51, as determined by the clock mechanism 52 although the index 73 is still opposite the zero index on the knob 64. The additional movement of the knob 64 and arms 66 and 75 (from Fig. 7 to Fig. 8) moves the fifteen-minute graduation on the knob 64 opposite the index 73 and winds the clock spring for fifteen minutes reverse movement of the shaft 51. During the total movement of the knob 64 (from Fig. 7 to Fig. 9), the timing mechanism 52 is

wound for a total of eighteen minutes operation, it being understood that the driving arm 75 is moved by the pin 76 as the knob 64 and its arm 66 are rotated from the position shown in Fig. 7 to the position shown in Fig. 9.

When the operator releases the knob 64 after moving the same to the position shown in Fig. 9, the tension spring 78 effects counterclockwise rotation of the knob 64 and the index carrier 69 relative the driving arm 75, to the position shown in Fig. 10. During this counterclockwise rotation of the knob 64, the driving arm 75 remains substantially stationary as the lost motion defined by the pin 76 and slot 77 is taken up.

During the transition of the apparatus from the position shown in Fig. 7 to the position shown in Fig. 8, the cam 39 and the arm 75, which moves with the cam 39 at all times, are moved clockwise. During the initial movement of the cam, the struck-up portion 27 of the switch arm 36 enters the arcuate recess 46 and, therefore, the switch arm 36 is disengaged from the contact 35. Further movement of the cam 39 clockwise disengages the switch arms 22 and 23 from their respective contacts 24 and 25 as the rollers 44 and 45 ride upwardly on the intermediate cam portions 53 and 54. In this open position, all of the switch arms 22, 23 and 36 are completely disengaged from any stationary contacts and it is in this open position of the switch that the arms 75 and 66 and the handle 64 assume the positions shown in Fig. 8.

Further clockwise movement of the cam 39 is effected as the handle 64 and arm 75 are moved from the position shown in Fig. 8 to the position shown in Fig. 9. During the initial part of this movement, the rollers 44 and 45 ride up on the outer cam surfaces 42 and 43 and, therefore, move the switch arms 22 and 23 into engagement with their stationary contacts 26 and 27, respectively. The switch is now in its second active position wherein a two-wire circuit is established, the terminals 16 and 18 being electrically connected to the terminals 32 and 28, respectively. It will be understood that no movement of the cam 39 is effected during the described counterclockwise movement of the arm 66 and knob 64 from the position shown in Fig. 9 to that shown in Fig. 10. Slow counterclockwise rotation of the driving arm 75, the arm 66 and the knob 64 towards the zero position of the latter is then effected by the clock mechanism. The cam 39 is also moved counterclockwise at this time. In Fig. 11, I have shown the relative positions of the driving arm 75, the arm 66 and the knob 64 in the zero position.

When the driving arm 75 and the knob 64 reach the zero position (Fig. 11), the rollers 44 and 45 ride down on the intermediate cam surfaces 53 and 54 and, therefore, move the switch arms 22 and 23 to their intermediate inactive or open positions. Movement of the driving arm 75 continues for an additional three minutes in the example described, or until the pin 76 engages the left-hand end of the slot 77 formed in the lever 66. At this time, however, it will be noted that the knob 64 and its arm 66 remain stationary, the index carrier 69 being in engagement with the stop 71 and the projection 79 on the knob 64 engaging the index carrier 69. It is during this three-minute additional operation that the tension spring 78 is extended to the position shown in Fig. 7. It is also during this three-minute operation that the rollers 44 and 45 become disengaged from the cam 39, whereby movement of the switch levers 22 and 23 into

engagement with the contacts 24 and 25 is effected. Toward the end of the additional three-minute movement referred to, the struck-up portion 47 of the switch lever 36 rides out of the arcuate slot 46 and depresses the switch lever 36 into its circuit-closed position. The apparatus, after this series of operations, is in the position shown in Figs. 1 to 7, inclusive, in other words, in its first active position.

The lost motion provided by the handle mechanism 63 prevents complete operation of the switching apparatus if the operator attempts to move the apparatus through the open position from its second active position to the first active position thereof. Manual movement of the knob in this direction will only actuate the apparatus to its "off" or inactive position wherein all of the switch blades 36, 22 and 23 are disengaged from any stationary contact. The position of the knob 64 and the arms 66 and 75 corresponding to this position of the switch is shown in Fig. 11. Movement of the apparatus to its first active position shown in the drawings from the "off" position is effected by the timing mechanism as described heretofore. This operation is incorporated into the device to prevent short circuits which might occur if the apparatus were manually actuated rapidly from the second active position to the first active position, as the movement of the switch arms 22, 23 and 36 would be substantially instantaneous if quickly operated. In other words, the switch arm 36 and the stationary contact 35 may be engaged before the breaking of the switch arms 22 and 23 from their contacts 26 and 27 or at least before any arc which might be drawn between these contacts were extinguished.

In the operation described, it will be understood that slippage occurs between the gear 57 and the resilient cup-shaped washer 58 during any manual movement of the shaft 51 either in a spring-winding direction or an unwinding direction and that the gear 57 is driven by the shaft 51 through the cup-shaped washer 58 during operation of the shaft 51 by the timing mechanism 52. An additional contact 81 is shown which is engageable with the switching arm 22 in the second active position of the switch. The contact 81 may be connected to a suitable indicating device, such as a lamp, which when energized would indicate that the switch is in its second active position.

From the foregoing description, it will be apparent that I have provided an improved time-controlled switching apparatus having a plurality of switch arms moved sequentially during the transition of the apparatus from one active position to a second active position and wherein short circuiting of the apparatus is precluded during the period of transition. As the possibility of a short circuit is greater when the switching apparatus is manually actuated in one direction, I provide novel means for preventing rapid manual movement of the apparatus in this direction. Operation of the switching apparatus under control of the timing mechanism completes the sequential switching operations, at least in part, when manual operation in this direction is to be effected. It will be understood that the specific form and number of switching blades are shown by way of example and that other arrangements of the blades and the number which are employed may be varied.

While I have shown my invention in but one form, it will be obvious to those skilled in the

art that it is not so limited, but is susceptible of various changes and modifications without departing from the spirit thereof, and I desire, therefore, that only such limitations shall be placed thereupon as are specifically set forth in the appended claims.

What I claim is:

1. In switching apparatus, the combination of a switching mechanism having a plurality of poles sequentially operated for effecting a plurality of preliminary switching operations during movement of the switching mechanism between first and second positions, manually-operated means for moving said switching mechanism from its first position through said preliminary switching operations to its second position, a lost motion device associated with said manually-operated means for preventing manual movement of the switching mechanism from its second position through its preliminary switching operations to its first position, a timing mechanism for moving the switching mechanism from its second position through said preliminary switching operations to its first position, and means for varying the period of time that the switching mechanism is retained in said second position.
2. In switching apparatus, the combination of timing mechanism having a member movable in two directions, said member being driven by the timing mechanism in one direction for a period of time predetermined by the amount of movement manually imparted to said member in an opposite direction, switch means including a plurality of sequentially operated switching devices actuated by said member to perform a plurality of successive switching operations as said member approaches an end of its movement, a handle for moving said member, and means associated with said handle for actuating said member in said opposite direction any selected amount but operative to move the member in said one direction only a lesser amount and to the position at which said successive switching operations are initiated, said successive switching operations being then effected at a relatively low rate of speed by said timing mechanism.
3. In switching apparatus, the combination of a double throw switch movable to first and second active positions, said switch being movable to an inactive position intermediate its active positions, a handle manually movable at will for actuating the switch from its first active position through the inactive position to its second active position, a lost motion device associated with the handle and providing for manual movement of the switch from its second active position to its inactive position, a timing mechanism actuated by said handle for moving the switch from its second active position to its inactive position and thence to its first active position at relatively low speed, and means for adjusting the timing mechanism so that the period of time that the switch is retained in its second position is variable.
4. In switching apparatus, the combination of a double throw switch movable to first and second active positions, said switch being movable to an inactive position intermediate its active positions, a timing mechanism having a member movable in one direction for initiating operation of the mechanism, said timing mechanism effecting movement of said member in a reverse direction at relatively low speed, a handle manually movable at will for moving said member in said one direction and in variable amounts for varying the period of time that the timing mechanism effects

reverse movement of the member, said handle being manually movable for effecting reverse movement of the member throughout only a portion of the movement that the member has been moved in said one direction, a connection between said member and said switch and effective to actuate said switch from its first active position through its inactive position to its second active position as the handle is moved in said one direction, said connection effecting movement of the switch from its second position to its inactive position only when the handle is manually actuated in its reverse direction.

5. In switching apparatus, the combination of a switching mechanism having a plurality of switching elements movable to first and second active positions, said mechanism effecting a plurality of preliminary switching operations during the period of transition between its first and second positions, a handle for moving the switching elements from their first active position through said transition period to their second active positions, a timer for moving the switching elements from their second active positions through the period of transition to their first active positions, means for varying the period of time that the switching elements are retained in their second active positions, and means for preventing movement of the switching means manually through said period of transition to their first active positions.

6. In switching apparatus, a timing mechanism including a member manually movable in one direction to a plurality of positions for varying the period of operation of the timing mechanism, said member being driven by said mechanism in a reverse direction, a switch movable from a first active position, through an intermediate inactive stage to a second active position as said member is manually moved in said one direction, said switch being moved from its second active position through its inactive stage to its first position as said member is driven in the reverse direction, and means associated with said manually operated member for preventing manual operation thereof in said reverse direction beyond said intermediate stage.

7. The combination of a double throw switch having first and second closed positions and an intermediate open position, manually operated means for moving the switch from its first closed position through its intermediate position to its second closed position, said means being effective to move the switch from its second closed position to its intermediate position only, a timing mechanism effective to move the switch from its second closed position through its intermediate position to the first closed position thereof, and means including said manually operated means for varying the period of time that the timing mechanism retains the switch in its second closed position.

8. In switching apparatus, the combination of a switch movable between first and second positions, a handle manually movable at will in one direction for actuating the switch from its first to its second position, means associated with the handle for preventing manual actuation of the switch from its second to its first position as movement is imparted to the handle manually in a reverse direction, a timing mechanism for actuating the switch from its second to its first position, means actuated by said handle for initiating operation of the timing mechanism as the handle is moved in said one direction, said last-mentioned means varying the duration of the period of operation of the timing mechanism dependent upon

the amount of movement manually imparted to the handle in said one direction.

9. In a switching mechanism, the combination of a switch movable between first and second positions, a timing mechanism for moving the switch in one direction, means for manually moving the switch in the opposite direction and for conditioning the timing mechanism for operation, said means including a handle having a plurality of graduations thereon, a carrier having an index thereon cooperating with said graduations, means connecting said handle and carrier and providing for movement of the latter as the former is actuated and means for limiting the movement of the carrier to a predetermined amount irrespective of the amount of movement imparted to the handle.

10. In a switching mechanism, the combination of a switch movable between first and second positions, a timing mechanism for moving the switch in one direction, manually operated means moving the switch in the opposite direction and for conditioning the timing mechanism for various periods of operation depending upon the amount of movement imparted to the manually operated means, said manually operated means including a handle having indicia thereon, a carrier including an index cooperating with said indicia, means defining a frictional connection between the handle and said carrier whereby the carrier moves with the handle as the latter is actuated and stop means for limiting movement of the carrier to a predetermined amount.

11. In a switching mechanism, the combination of a switch movable between first and second positions, a timing mechanism for moving the switch in one direction, means including a handle member for manually moving the switch in the opposite direction and for conditioning the timing mechanism for operation, a carrier member, means connecting said handle and carrier members and providing for movement of the latter as the former is actuated, means for limiting movement of the carrier member to a predetermined amount irrespective of the amount of movement imparted to the handle member, and cooperating graduation and index means on said members.

12. In switching apparatus, a timing mechanism including a member manually movable in one direction to a plurality of positions for varying the period of operation of the timing mechanism, said member being driven by said mechanism in a reverse direction, a switch movable from a first active position, through an intermediate inactive stage to a second active position as said member is manually moved in said one direction, said switch being moved from its second active position through its inactive stage to its first position as said member is driven in the reverse direction, means associated with said manually-operated member for preventing manual operation thereof in said reverse direction beyond said intermediate stage, a carrier member, means connecting said manually-operable member and carrier member and providing for movement of the latter as the former is actuated, and means for limiting movement of said carrier member to a predetermined amount corresponding to the amount said manually-operated member is movable in said reverse direction solely by said timing mechanism.

13. In switching apparatus, timing mechanism having a member driven thereby in one direction for a time predetermined by the amount said

member is moved in an opposite direction, switch means actuated by said member to perform a plurality of successive switching operations as said member approaches the end of its predetermined movement, a handle mounted on said member for manual manipulation thereof, a lost-motion connection between said handle and member, resilient means for biasing said handle in said one direction with respect to said member, and stop means for said handle positioned to stop movement of said handle when moved in said one direction, whereby said member may be moved a further distance in said one direction by said mechanism, while stressing said resilient means, to complete said switching operations.

14. In switching apparatus, timing mechanism having a member driven thereby in one direction for a time predetermined by the amount said member is moved in an opposite direction, switch means actuated by said member to perform a

5 plurality of successive switching operations as said member approaches the end of its predetermined movement, a handle mounted on said member for manual manipulation thereof, a lost-motion connection between said handle and member, resilient means for biasing said handle in said one direction with respect to said member, stop means for said handle positioned to stop movement of said handle when moved in 10 said one direction, whereby said member may be moved a further distance in said one direction by said mechanism, while stressing said resilient means, to complete said switching operations, indicating means frictionally associated with said member so as to be movable therewith, and means limiting movement of said indicating means with said member to an amount corresponding to the movement of said member necessary to complete said successive switching operations.

15 20 EARL K. CLARK.
